CLAIM

The ornamental design for a shoe upper, as shown and described.

DESCRIPTION

FIG. 1 is a front perspective view of a shoe upper showing my new design;

FIG. 2 is a lateral front perspective view thereof;

FIG. 3 is a lateral side view thereof;

FIG. 4 is a medial view thereof;

FIG. 5 is a front view thereof;

FIG. 6 is a rear view thereof; and,

FIG. 7 is a top view thereof.

The broken line showing of the bottom edge and the remained of the shoe upper is for illustrative purposes only and form no part of the claimed design.
